F. J. MEAGHER

DOOR HANGER

Original Filed Nov. 2, 1922

UNITED STATES PATENT OFFICE.

FRANCIS J. MEAGHER, OF NEW YORK, N. Y.

DOOR HANGER.

Application filed November 2, 1922, Serial No. 598,615. Renewed June 3, 1924.

To all whom it may concern:

Be it known that I, FRANCIS J. MEAGHER, a citizen of the United States, residing in the city of New York, borough and county of Queens, in the State of New York, have invented a certain new and useful Improvement in Door Hangers, of which the following is a specification.

The invention relates to antifriction supports for sliding doors for elevators and like purposes, and the object of the invention is to provide a hanger of simple and economical construction which shall permit the door to hang closely, operate easily and noiselessly, be strong and durable, and readily installed.

A further object is to provide adjusting means whereby the door may be successfully hung and operated upon walls or casings having irregular surfaces or slightly out of the perpendicular without requiring preliminary work in altering the wall surface.

Another important object is to provide means for inclosing the tracks and moving parts of the mechanism to exclude dust and abrading grit tending to undue wear, and also to provide means for preventing upward bucking movements of the door in its sliding travel.

The invention consists in certain novel features of construction and arrangements of parts by which the above and other objects are attained, to be hereinafter described and claimed.

The accompanying drawings form a part of this specification and show an approved form of the invention.

Figure 1 is an end view of the improved hanger and a portion of a door suspended thereby, showing the relation of the door to the adjacent wall.

Figure 2 is a corresponding front view, partly in vertical section and also broken away to show certain interior portions.

Figures 3, 4 and 5 are vertical transverse sections through the hanger, on a larger scale, taken on the lines 3—3, 4—4, and 5—5 respectively in Figure 2.

Similar reference numerals indicate the same parts in all the figures.

The door is marked 10 and the adjacent wall or door casing is marked 11. Upon the casing above the line of the door-opening is a series of outwardly projecting brackets 12 which support the hanger by 55 bolts 13 extending through the upper face or deck of a hollow housing formed of heavy sheet metal to a rectangular box-like cross-section, having a longitudinally centrally located open slot 15 in its bottom extending its entire length.

The heads 16 of the bolts 13 lie beneath the upper face or deck 14 of the housing and the bolts extend through slots 17 in the horizontal arms of the brackets 12, thus permitting the housing to be adjusted toward or from the wall or casing 11 as may be required.

Beneath the deck 14 and receiving the heads 16 of the bolts 13 is a channel-iron or longitudinally extending trough 18 set with its upwardly projecting flanges in contact with the inner face of such deck and is secured thereto by slitting the bottom of the trough at the ends along the junctions with the flanges and bending upwardly the tongues 19 thus formed and securing them to the deck 14 by rivets as at 20. The width of the channel or trough is such as to receive and engage the heads 16 of the 70 bolts 13 and hold the latter against turning when the nuts 21 are turned.

The sides 22 of the housing extend downwardly and terminate in flanges 23 turned inwardly to form the margins of the slot 15, 85 and 24 are tracks of rectangular section received in and reinforcing the angles formed at the junctions of the flanges with the sides. The tracks are joined to the housing by rivets 25 extending through the sides 22, 90 and the upper face of each is provided with a shallow groove 26 serving as a raceway for a series of antifriction balls 27 running on each track, equidistant from the centre line of the slot 15.

A movable rail extending longitudinally of the housing and inclosed therein, is supported on the balls 27 and carries the door. The rail is of Y-section, preferably in two like parts joined together as shown, to

a single narrow base portion 28 projecting downwardly through the slot 15, and two outwardly curved flanges or wings 29 shaped to match the curvature of the balls 5 27 and ride thereon.

On the outer face of the projecting portion of the base 28 are riveted straps 30 having lugs 31 receiving bolts 32 extending therethrough and through the ears 33 of a 10 depending yoke 34 which receives a vertical bolt 35 secured to the upper edge of the door by an angle plate 36 on the latter. The bolt 35 extends through a transverse slot 37 in the yoke 34 to permit the door 15 to be adjusted inwardly or outwardly relatively to the wall and independently of the housing.

In the central angular groove 38 formed by the oppositely curved wings 29 of the 20 rail-head, is a series of balls 39 seated in the raceway thus formed, with their upper faces in rolling contact with the under face of the trough 18, thus holding the rail against upward movement and insuring smooth 25 noiseless operation of the door in its opening and closing movements.

A transverse pin 40 joining the sides 22 of the housing at their outer ends serves as a stop to limit the opening movement of 30 the door. The closing movement may be limited by similar or any approved latching means, not shown.

The balls in the three series 39, 27 and 27 are held in the proper spaced relation by a 35 ball carrier comprising a freely moving plate 41 having angularly arranged downwardly projecting flanges or ribs 42, with spaced openings 43 along the centre line of the plate 41 to receive the balls 39, and openings 44 in the ribs 42 to receive the balls 27 which also support the carrier. The openings are formed with ears 45 aiding to hold the balls in position.

Thus constructed and arranged the parts 45 are strong and durable. The door is suspended on two balanced series of balls running on easily and accurately levelled tracks, with the strains of suspension so disposed as to avoid any tendency of the tracks 50 to spread, and the upper series of balls 39 prevents lifting or jumping in the opening and closing operations. The slot 15 through which the base of the rail protrudes may be very narrow, and all the parts subjected to 55 wear are inclosed within the housing and thus protected. The vertical and transverse adjustments afforded by the slots in the brackets 12 and yoke 34 permit the door to be so hung as to serve successfully 60 on walls or casings having irregular surfaces or inexactly plumbed.

I claim:—

1. In a door hanger, a housing having a slot in its bottom, a track within the housing upon opposite sides of said slot, a rail

of substantially Y-section with its lower portion extended through said slot, balls interposed between the out-turned portions of said rail and said tracks, and means bridging said out-turned portions and having depending portions serving to retain said balls in place. 70

2. In a door-hanger, a housing comprising a deck, sides and bottom and having a longitudinally extending slot in said bottom formed by inwardly projecting flanges on said sides, tracks mounted in the angles formed by said sides and flanges and each having a raceway in its upper face, a series of balls in each raceway, a rail inclosed in said housing and projecting through said slot and having wings riding on said balls, a channel-iron on the under face of said deck, said rail having a centrally located raceway, a series of balls in the latter between said rail and channel-iron, bolts extending through said deck with their heads inclosed in and held by said channel-iron, means coacting with said bolts for securing said housing to a wall, and means for suspending a door from said rail. 80

3. In a door hanger, a housing having a slot in its bottom, a track within the housing upon opposite sides of said slot, a rail of substantially Y-section with its lower portion extended through said slot, balls interposed between the out-turned portions of said rail and said tracks, and means bridging said out-turned portions and having depending portions serving to retain said balls in place, said bridging means having openings, and balls in said openings bearing upon the upper face of the rail along its medial line. 95

4. In a door-hanger, a housing comprising a deck, sides and bottom and having a longitudinally extending slot in said bottom formed by inwardly projecting flanges on said sides, tracks mounted in the angles formed by said sides and flanges and each having a raceway in its upper face, a series of balls in each raceway, a rail inclosed in said housing and projecting through said slot and having outwardly curved wings matching the contour of said balls and riding thereon, a raceway formed by the angular groove between said wings, a series of balls in such groove between said rail and deck, means for securing said housing to a wall, and means for suspending a door from 105 said rail. 110

5. In a door-hanger, a housing comprising a deck, sides and bottom and having a longitudinally extending slot in said bottom formed by inwardly projecting flanges on said sides, tracks mounted in the angles formed by said sides and flanges and each having a raceway in its upper face, a series of balls in each raceway, a rail inclosed in said housing and projecting through said 125 130

slot and having outwardly curved wings matching the contour of said balls and riding thereon, a raceway formed by the angular groove between said wings, a series of balls in such groove between said rail and deck, means for securing said housing to a wall, means for suspending a door from

said rail, and a ball carrier above said rail and partially inclosing said wings and having spaced openings receiving the balls of 10 each series.

In testimony that I claim the invention above set forth I affix my signature.

FRANCIS J. MEAGHER.
